UNITED STATES PATENT OFFICE.

ARTHUR SCHAEFFER, OF BERLIN, GERMANY.

SAFETY-FASTENER.

SPECIFICATION forming part of Letters Patent No. 764,153, dated July 5, 1904.

Application filed December 16, 1902. Serial No. 135,396. (No model.)

To all whom it may concern:

Be it known that I, ARTHUR SCHAEFFER, a citizen of the Kingdom of Prussia, and a resident of Prinzessinenstrasse 10, Berlin, in the 5 Kingdom of Prussia, German Empire, have invented certain new and useful Improvements in Safety-Fasteners, of which the following is a specification.

My invention relates to improvements in 10 safety-fasteners for necktie-pins, neckties, pin-brooches, waist or front shirts, and the like, and has for its object to give to the fastening of said articles a greater security than ever before.

15 A further object of my invention is to enable the user of said new safety-fastener to secure by one and the same revolving motion the connection of two different articles either to each other or to a third object, so that by 20 only one motion of the fastener either a pin may be securely fastened to the tie or, besides said pin fixation, the tie itself may be yet secured to the shirt or any other suitable part of the garment.

25 My invention has the further object to prevent any damage to the fabric in which the one part of the new fastener is inserted, as well as prevent a disconnecting of the parts fastened to each other by any accident what- 30 ever.

I attain these objects by the mechanism illustrated in the accompanying drawings, in which—

Figure 1 shows my new fastener applied to 35 the end or point of a necktie-pin shaft. Fig. 2 is a front view of the fastener drawn at a larger scale. Fig. 3 is a side view. Fig. 4 shows the fastener in horizontal section and seen from above. Fig. 5 illustrates in side 40 view a modification of the new fastener—viz., as waist-shirt holder; and Fig. 6 shows said modification in front view.

My new safety-fastener consists of a plate 1, through which a pivot 2 passes. Said pivot 45 2 is provided with a screw-thread which engages a thread in the plate 1; further, carries the pivot 2 at its upper end a milled button 3 or other suitable device, by means of which it can be revolved, and at its lower end a plate 50 4, to which a helically-curved pin 5 is at-

tached. In the forms illustrated it is assumed that all points of the center line of the said pin 5 are at equal distances from the axis and that in the line of the latter a short straight guide-pin is arranged. Between the plate 1 55 and the button or head 3 a plate-like part 9 is arranged, which by the help of the perforation 10 is mounted upon the pivot 2 in such a manner that when screwing the pin 5 into the fabric said part 9 without revolving with 60 the pivot 2 is more and more moved and pressed against the plate 1.

According to the form illustrated in Figs. 1 to 4, this part 9 is connected with a finger or stud 11, projecting sidewise into a cut-out of 65 the tube 7, fastened to the plate 1. This tube 7 serves as receptacle for the shaft or, better, for the shaft-point of a necktie-pin.

The novel feature of my said invention, therefore, lies especially in the fact that by inserting the helical pin 5 into the fabric—i. e., that by the revolving motion of the button 3—the shaft-point 8, by virtue of the finger 11 moving against the tube 7, will firmly be fastened within the latter and simultaneously the helical pin rotated round its axis, thereby fastening same within the fabric. A further feature of my invention is to be seen in the limitation of the rotation of the helical pin round its axis, which is done by the finger 11 abutting against 75 the shaft 8.

In using the helical - pin fasteners injury through the sharp points of the pins 5 might be easily incurred. It is therefore necessary to protect the said points when the fastener 85 is not in use in such a manner that injury is impossible, but so that the movability of the fastener is in no way interfered with. For this purpose a spring-tongue 6, for instance, can be arranged on the under side of the plate 90 1 or, as illustrated in Figs. 1 to 4, at the under side of a finger projecting from said plate in such a manner that the said tongue covers that place which the point of the helical pin will occupy when fully unscrewed. When being screwed in, first the point of the pin will move from under the said tongue, so that it can enter the fabric, and then by further rotating the pin its one or two or more windings 95 will come forth. In this manner finally the 100

whole helical pin is moved from under said tongue 6, the free end which entirely abuts in fastenings position of my new safety device against the respective side of plate 1. With 5 this kind of device also shoulders or any other suitable elements for limiting the rotation of the pin when unscrewing are essential in order that when screwed out the point of the pin will always pass exactly underneath or in 10 the plane of the resilient tongue.

In the modification shown in Figs. 5 and 6 my invention is used as fastener for a waist-shirt or the like. The only difference in 15 construction between this modification and the device above described lies in the fact that the plate-like part 9, with its finger 11, is replaced by a gripper 13, which with its one end is elastically connected to the plate 1. Further, said plate 1 bears instead of the tube 7 20 a prolongation or nose, which serves as resisting-plate for the gripper 13. When using said modification, the edge of the waist-shirt is placed between the nose of plate 1 and the gripper 13 and then the button 3 or helical

pin 5 screwed in, for example, into the waist- 25 band of the under trousers or any other suitable part of the user's clothing.

Having now particularly described and ascertained the nature of my said invention and in what manner the same is to be performed, 30 I declare that what I claim is—

A safety-fastener for necktie-pins, pin-brooches, neckties and the like comprising in combination a helical-pin fastener of suitable construction and a clamp whose parts are 35 adapted to move toward each other, when the helical pin is screwed into the fabric and from each other when the pin-fastener is unscrewed, substantially as described and shown and for the purpose set forth. 40

In witness whereof I have hereunto signed my name, this 1st day of December, 1902, in the presence of two subscribing witnesses.

ARTHUR SCHAEFFER.
